UNITED STATES PATENT OFFICE.

ERWIN F. SIFTROTH, OF EASTON, PENNSYLVANIA.

COALING DEVICE.

Application filed April 12, 1921. Serial No. 460,854.

To all whom it may concern:

Be it known that I, ERWIN F. SIFTROTH, a citizen of the United States, residing at Easton, in the county of Northampton and State of Pennsylvania, have invented new and useful Improvements in Coaling Devices, of which the following is a specification.

This invention relates to coaling devices for locomotives, the principal object of the invention being to provide means for supplying the tender of the locomotive with coal as the locomotive moves under the coaling device and without necessitating the stopping of the locomotive.

Another object of the invention is to provide a plurality of coal receiving drums normally in communication with the coal hopper so as to be filled with coal therefrom, with means for partially rotating the drums when the locomotive passes under the same to cause the coal therein to drop into the tender and at the same time cut off the feed of the coal from the hopper to the drum.

A further object of the invention is to provide a trip device on the locomotive or its tender for actuating the drums with means for holding said trip device in inactive position when desired.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a view looking towards one side of a coaling device constructed in accordance with my invention.

Figure 2 is a view looking towards the opposite side.

Figure 3 is a vertical section on line 3—3 of Figure 1.

Figure 4 is a section on line 4—4 of Figure 3.

Figure 5 is a view showing the locomotive under the device and with one of the drums in discharging position.

Figures 6, 7 and 8 are enlarged detail views of the trip device on the tender.

In these views 1 indicates a coal hopper

supported on the framework 2 which is located adjacent the track 3. A plurality of chutes 4 project from the bottom of the hopper and said chutes are inclinedly arranged as shown. At the lower end of each chute is rotatably mounted a drum 5 by means of the pintles 6 projecting from the ends of the drum and engaging bearings in the extensions of the sides of the chute. Each drum is provided with an opening 7 and a delivery plate 8 is secured to the drum adjacent said opening, said plate being so arranged that the coal passing from the opening will pass down the face of the plate. Each drum is normally held with its opening 7 uppermost and within the chute so as to receive the coal passing down the same by means of a weight 9 which is secured to the drum. In this position of the drum the delivery board 8 extends upwardly in front of the chute.

A triangular lever 10 is pivoted to the frame 2 adjacent each chute and one end of said lever is connected with the board 8 by the spring 11 so that when the other end of said lever is struck and the lever caused to swing downwardly upon its pivot tension will be placed upon the spring so that the board 8 will be moved downwardly to rotate the drum and bring its opening into discharging position.

The tender 12 of the locomotive 13 carries a trip device 14 which consists of a frame 15 pivotally mounted in brackets 16 secured to one side of the tender 12. A roller carrying member 17 is pivoted to the ears 18 on said frame, said member having a depending part 19 which is adapted to engage a lug 20 on frame 15 to support said member in horizontal position. The roller 21 is carried at the forward end of the member 17. Arms 22 have their forward ends bent and pivoted to the side edges of member 17 by the pivot pin 23 and said arms are connected to a handle member 24 at their rear. This handle member is provided with an extension 25 which engages a curved guideway 26 on the top of the tender, the ends of the guideway being provided with recesses 27 for receiving the enlarged end of the extension 25 to lock the parts against movement at each end of the guideway.

It will be seen from Figures 6, 7 and 8 that when the trip is to be moved into operative position to actuate the trip levers 10 the handle member 24 is moved to the rear-

ward or outer end of the guideway so as to move the roller to the position shown in said figures, where it will engage the levers 10 to open the chutes and thus deliver the coal 5 from the chutes to the tender.

If it is not desired to take on a fresh supply of coal the handle member 24 is swung to the opposite end of the guideway and this movement will swing the frame 15 inwardly 10 against the side of the tender and at the same time will swing the roller carrying member 17 upon its pivot so that said parts will not engage the levers 10 and will be prevented from striking objects along the 15 track.

The coal in the drum will pass through the opening and pass down the board 8 into the tender. As soon as the tender passes from under the drum and the lever 10 is 20 released from the roller the weight 9 will return the drum to normal position so that it will be filled again with coal which passes into the same from the chute and hopper. As the locomotive passes along the roller 25 will engage the next tripping lever so that the coal in the next drum will be discharged into the tender. Thus the tender will be filled with coal without stopping the locomotive.

I prefer to make the roller 21 adjustable in the member 17 by forming curved slots 17' in said member 17 for receiving the pintles of the roller. The slots are so formed as to provide three bearings for the pintles 35 so that the roller can be placed in any one of three positions. By adjusting the roller the discharge of coal from the chutes can be so controlled as to place the coal in different parts of the tender.

I may also provide cables 11' for connecting the boards 8 with the levers 10 so as to relieve the springs 11 of the load after the parts have started to move to discharging 40 position.

It is thought from the foregoing description that the advantages and novel features of my invention will be readily apparent. I desire it to be understood that I may make changes in the construction and in the 50 combination and arrangement of the several parts, provided that such changes fall within the scope of the appended claims.

What I claim is:—

1. An apparatus of the class described 55 comprising a framework located adjacent a

track, a hopper supported by the framework, a chute depending from the hopper, a rotatable drum mounted at the end of the chute and having an opening therein, weighted means for normally positioning the 60 drum with the said opening in register with the chute, a deflecting plate connected with the drum adjacent the openings, a tripping lever, means for connecting the lever with the plate and a tripping device for engaging 65 said lever to cause the same to rotate the drum into discharging position.

2. A coaling device comprising a hopper, a rotatable drum normally positioned to receive the discharge of the hopper and having 70 a delivery portion, a trip lever for rotating the said drum into a delivery position, said trip lever having one end disposed to lie in the path of a moving coal-car or other vehicle, and a tensionable connection 75 between the other end of the said lever and the said drum.

3. A coaling device comprising a plurality of aligned hoppers having discharge chutes, a trip operated discharge mechanism associated with each chute and including respectively a weighted drum normally positioned with its receiving opening in line with the chute, a pivoted lever and a tension spring connection between one end of the lever and the said drum, and a vehicle-carried trip arm constrained to move in a path coincident with the aligned hoppers and having engagement with the levers for successively pivoting the latter to tension the springs 85 for rotating the said drums into discharging 90 position.

4. A coal device for coaling locomotive tenders including a hopper, a delivery element for receiving the discharge of the said hopper, means for normally maintaining the delivery element in a non-delivering position and including a pivoted lever, lever-actuating means associated with the tender and comprising a vertical frame pivoted thereto for swinging movement in a horizontal plane, a horizontally disposed arm mounted upon said frame having its outer end presenting lever-engaging means, a handle at the inner end of the arm, an arcuate track mounted on the tender, and an extension carried by the said handle and constrained to move along the said track. 100

In testimony whereof I affix my signature.
ERWIN F. SIPTROTH.
